(57) **CLAIM**

The ornamental design for an integrated dosage cup and child resistant cap, as shown and described.

DESCRIPTION

FIG. 1 is an isometric front view of an integrated dosage cup and resistant cap showing the new design;

FIG. 2 is a front view showing the new design;

FIG. 3 is a right side elevational view showing the new design

FIG. 4 is a rear view showing the new design

FIG. 5 is a left view showing the new design;

FIG. 6 is a top view showing the new design;

FIG. 7 is a bottom view showing the new design;

FIG. 8 is a cross-sectional view taken in the direction of line 8-8 of FIG. 4 showing the new design; and,

FIG. 9 is an isometric view of bottom, left, front sides showing the new design.

In the drawings, the broken lines showing portions of an integrated dosage cup and child resistant cap depict environment and form no part of the claim.
